PIPE PELLET

Clair Wynecoop, Wellpinit, Wash.

Application May 19, 1945, Serial No. 594,670

1 Claim. (Cl. 131—3)

1

This invention relates to tobacco pellets and it is one object of the invention to provide a pellet formed of tobacco of the type used in pipes; the tobacco being packed in a jacket formed of filtering material and being of such shape and dimensions that it will fit snugly in the bowl of a pipe and burn in the usual manner, the filter serving to prevent nicotine or moisture from penetrating the wood or other material from which the pipe is made and causing the pipe to become strong.

Another object of the invention is to provide a tobacco pellet which has its upper end covered by a cap formed of waxed paper, or equivalent material, and serving to prevent the tobacco from drying before being used.

Another object of the invention is to provide a tobacco pellet of such form that a relatively large number may be packed in a container with a strip of material extending between tiers of pellets and having an upper end in such position that it may be grasped and drawn upwardly to raise the pellets resting upon the strip so that they may be readily removed from the container.

The invention is illustrated in the accompanying drawings wherein:

Figure 1 is a perspective view of the improved pellet.

Figure 2 is a vertical sectional view taken diametrically through the pellet.

Figure 3 is a sectional view showing the pellet pressed into a pipe for smoking.

Figure 4 is a view showing a number of the pellets packed in a container in which they are sold.

This improved tobacco pellet, which is indicated in general by numeral 1, consists of a pre-determined quantity of tobacco which is moulded under sufficient pressure to form a pellet or shaped mass of tobacco 2. This pellet is packed in a jacket 3 formed of non-burnable filtrable material which will absorb nicotine and prevent a pipe from becoming soggy and strong. The filter also serves to cool smoke drawn from the bowl 4 of the pipe through the smoke passage 5 of the stem 6. The jacket or filter 3 conforms to the shape of the pipe bowl and has its bottom 7 thick and its walls gradually reduced in thickness towards its upper end. The thickened lower portion or bottom of the filter prevents nicotine and moisture from penetrating the bottom of the filter and entering the smoke passage. The pellet fits snugly into the pipe bowl and when slight pressure is applied to its upper end it will be spread and a tight fit created between the pellet and the pipe. After the filter or jacket has been filled with tobacco a cap 8 formed of waxed paper which is air proof is applied to cover the top of the pellet and prevent the tobacco from drying and since this cap is formed with a tab 9 it may be readily removed when the pellet is to be used.

2

The pellets are packed for sale in a container 10 and arranged in tiers as shown in Figure 4. A strip 11 is first thrust into the container with its lower end portion resting upon the bottom of the container. A row of pellets are then set in place upon the lower portion of the strip and the strip folded so that it extends the pellets in covering relation thereto and another tier of pellets set in place upon the strip, this being repeated until the container is filled with tiers of pellets separated by portions of the strip. The upper end portion of the strip overlies the upper tier and by grasping the strip and exerting upward pull the pellets may be lifted to a position in which they may be individually grasped and removed from the container.

Having thus described the invention, what is claimed is:

1. A tobacco pellet comprising a cup-shaped jacket formed of filtering material and being open at its top and having a bottom and an annular wall, the jacket being circular in cross section and its bottom being hemispherical and gradually decreasing in thickness from its center towards its marginal edge portions which merge into the annular wall, the said annular wall gradually decreasing in thickness from its junction with the bottom to its upper end, a mass of compressed tobacco complete filling said jacket and having a flat upper surface flush with the upper edge of the annular wall of the jacket, and a removable cap of thin air moisture proof paper resting flat upon the upper surface of the tobacco and the upper edge of the annular wall of the jacket and having a depending marginal flange fitting snugly about the annular wall in close fitting contacting engagement therewith and provided at a point about its circumference with a tab projecting outwardly from the annular wall of the jacket.

CLAIR WYNECOOP.
